UNITED STATES PATENT OFFICE.

NICHOLAS J. CONRAD, OF CHICAGO, ILLINOIS, ASSIGNOR TO SCHWEITZER & CONRAD, OF CHICAGO, ILLINOIS, A CORPORATION OF ILLINOIS.

FUSE DEVICE.

1,220,152.

Specification of Letters Patent. Patented Mar. 20, 1917.

Application filed April 4, 1914. Serial No. 829,556.

To all whom it may concern:

Be it known that I, NICHOLAS J. CONRAD, a citizen of the United States, residing at Chicago, in the county of Cook and State 5 of Illinois, have invented a certain new and useful Improvement in Fuse Devices, of which the following is a full, clear, concise, and exact description, reference being had to the accompanying drawings, forming a 10 part of this specification.

My invention relates to fuse devices, and especially to a fuse device adapted for extra high potential service.

Prominent objects of the invention are to 15 provide a simple and efficient device of the character specified; to arrange for accuracy and efficiency in operation; to prevent injury or damage to the device as a result of operation; to arrange for the ready restoration 20 of the device to operative condition after operation; and to secure the foregoing and other desirable results in a simple and practical manner.

In the accompanying drawings Figure 1 25 is a vertical longitudinal section of a fuse device embodying my invention;

Fig. 2 is a cross section taken on line 2—2 in Fig. 1;

Fig. 3 is a view similar to Fig. 2, of a 30 modified form of the invention;

Fig. 4 is a view similar to Fig. 3 of another modification;

Fig. 5 is a longitudinal vertical section 35 of another modified form of device;

Fig. 6 is a view taken on line 6—6 in Fig. 5;

Fig. 7 is a view of another modification;

Fig. 8 is a cross section taken on line 8—8 in Fig. 7.

Fig. 9 is a view similar to Fig. 7 showing 40 the method of restoring the device to operative condition after operation.

Referring first to Figs. 1 and 2, I show a device having a tubular member 1, preferably made of insulating material such as glass. The lower end of this member is provided with a cap member 2, preferably made of metal and adapted to close the lower end of the tube 1. This cap 2 has a 45 wing or blade 3 by which connection may be made with contact jaws. At the upper end of the tube 1 is another cap member 4, preferably made of metal and adapted to close the upper end portion of the tube 1.

This member 4 also has a wing or lug 5 for contact purposes. Mounted upon the

top of the member 4 is a cover or top piece 7, which may be of either metal or insulating material. This is fitted to the top of the member 4, as for example by providing the latter with grooves into which the lower edges of the top 7 may fit as shown in Fig. 1. The top 7 is preferably sealed in position. If it is made of metal it may be preferably soldered in place. If made of insulating material it may be secured in place by shellac. The cap member 4 has a central aperture 8 smaller at its lower end than at its upper end so as to form a shoulder 9. Upon this shoulder is placed a disk 10 which is preferably made of insulating material such as fiber. This disk 10 is perforated, having a central aperture, through which is extended a post or rod 11 which extends down into the tube 1, and forms a terminal. The lower end of the rod 11 is fitted into a coupling 12, to which also is fitted the upper end of a flexible conductor 13, which latter extends down in the tube 1 and is soldered to the bottom of the same. The object of this arrangement is to permit the upper rod 11 to be replaced by another rod if the upper end of the same becomes burned or mutilated by the fuse in operating. A fine wire 14 which may be 80 of steel is extended from side to side of the upper face of the cap member 4, bridging the central opening of the same as shown in Fig. 2, and passing through an aperture in the upper end of the part 11. A fuse 16 85 extends from one side of the cap member 4 to the central bar 11, being conveniently soldered in position at both ends. A spring 18 is arranged within the tube 1, being secured at its lower end to the cap member 2 90 and at its upper end to the lower end of the bar 11. The spring 18 tends to draw the bar 11 downwardly, but this tendency is opposed by the fine wire 14. If desired a movable member 19 having a central 95 orifice 20 which is preferably cone shaped may be employed, in which case it would be secured for movement with the bar 11 as by cross piece 21.

Thus in operation the current will pass 100 between the cap members 2 and 4 passing through the conductor 13 and bar 11, and through the fine wire 14 and fuse 16. An abnormally strong current will cause operation 110 of the device, by first fusing the fuse 16, as a result of which all of the current is thrown upon the fine wire 14, which

thereupon fuses also. This releases the bar 11 which forms a movable fuse terminal, permitting the spring 18 to draw the said terminal downwardly and with it the member 19 whose conical aperture 20 forces or directs liquid 22, preferably confined in the tube 1, upwardly toward the top of the member 1. As a result the gap at the fuse opening is widened by the downward movement of the bar or terminal 11, and the liquid is directed into such gap so as to extinguish the arc by the action of the liquid directing member 19.

It will be seen that the fuse 16 and its coöperating fine wire 14 which also has a fuse action, are really outside of the insulating tube 1 and are confined in a separate chamber which may be called an explosion chamber. This makes it impossible for the explosion or operation of the fuses or either of them to damage the tube 1 which when made of glass is, of course, more or less fragile and breakable. To restore the operative condition of the device after operation a new fuse and fine wire may be inserted by removing the top 7 and then replacing the same. The top 7 acts as a vent, being blown off when the fuse operates. The disk 10, is, it will be seen, firmly seated against movement into or toward the tube 1. Therefore operation or blowing of the fuse within the fuse chamber does not have any effect in forcing the disk 10 downwardly. However, when the spring 18 is actuated, causing an arc to be drawn more or less into the tube 1 at the end of the terminal or post 11, any excessive pressure so generated within the tube 1 will cause the disk 10 to be blown outwardly, thereby permitting excess pressure to be discharged out through the upper end of the tube 1 and so protecting said tube from breakage or damage.

In Fig. 3 I show a modification in which there are used three fuses 16—16, instead of one, as shown in Fig. 2, and in Fig. 4, four such fuses are used.

Referring to the device shown in Figs. 5 and 6, I show a device quite similar to that of preceding figures, but having a slight difference in construction of the explosion chamber containing the fuse. In this construction a metal disk vent 25 is arranged at the top of the metal cap member 4^a, the side walls 26 of said member being extended up so as to form sufficient space for the explosion chamber below the disk 25. This metal disk 25 is preferably soldered to the upper edges of the walls 26 by low temperature solder. The under side of the disk 25 is preferably provided with a layer 27 of asbestos or similar heat insulating material. In this case there are shown a plurality, preferably six, main fuses 28—28, which fuses are held in place by screws 29—29. A cross wire 30 of steel or other material is

also shown, the same being held by screws 31—31. The explosion chamber 32 may be filled with inert air or filler as the case with inclosed fuses. This device is also designed for use with the ferrule type clip instead of 70 knife blade clip, the cap members 4^a and 2^a not being provided with blades or lugs as in the previous construction.

In the arrangement shown in Figs. 7, 8 and 9 I show a structure particularly adapted to serve as a refillable fuse. This construction involves a removable top member 34 having a screw threaded connection with the upper annular rim portion 35 of the cap member 4^b. The top member 34 may be removed, it will be seen, by unscrewing it from the top of the member 4^b. As a preferred arrangement the screw threads on the parts 34 and 35 are preferably shellacked so as to hermetically seal the joint between said parts. 80 A gasket 36 may be used if desired. The top member 34 is preferably constructed with a metallic disk 37 which may be soldered to the upper edge of the rim portion 34, low melting solder being preferably used. The member 4^b is preferably provided with knobs or projections 38 and the top member 34 with knobs or projections 39 by which wrenches or special tools may be engaged to turn said parts relative to one another. 90

As a further improvement the post or rod member 11^a is made of two parts 40 and 41 joined together and the upper part 40 is provided with a screw 42 holding the fuses 43 in position. When the fuse blows the top member 34 may be unscrewed and removed and then a screw driver may be inserted to unscrew the screw 42 and then a long rod 44, (Fig. 9) may be inserted in the device and caused to engage the upper end of the rod portion 40 as by screwing it into the top end of said rod, so that the rod 44 may then be lifted and the post 11^a drawn up to permit resetting of the fuse. The disk 37 will be torn or blown off when a certain pressure is 100 reached by the blowing of one or more of the fuses in the fuse or explosion chamber 45. The part 40 of the post 11^a may be removed and a new part substituted in its place if the first mentioned part is burnt by arcing during severe operation. It will be seen that the customer or user may re-fuse these fuse devices himself without soldering of any kind and by the use of ordinary simple tools. The customer or user may be provided with 110 extra terminals 40 extra annular rings or top members 34 with the thin sheet metal vents soldered thereon and with various sizes of fuse wire and arc extinguishing liquid such as carbon tetra-chlorid, so that he may re-fuse and refill the devices. 115

In the appended claims I employ the phrase "relatively non-fusible" as designating a part which in the normal action of the device is not required to be fused and is not 120 130

intended to be subject to fusion. This result is secured preferably by arrangement and proportioning of the parts.

It will be understood that changes and modifications may be made without departing from the spirit of the invention. It will be seen as one modification, for example, that the liquid directing member 19 may be omitted and the device constructed without such member. Other changes and modifications will also be apparent.

What I claim as my invention is:

1. In combination a relatively stationary terminal, a relatively movable terminal, said terminals being relatively non-fusible, a fuse connecting said terminals, means for moving said movable terminal away from the stationary terminal in a direction substantially at right angles to the length of the fuse and non-conducting means lying at the corner between the movable terminal and the fuse for causing the arc to be drawn about said corner.

2. In combination a fuse, a stationary terminal engaging the ends of the fuse, a movable terminal engaging the fuse between said ends, said terminals being relatively non-fusible, means for moving one of said terminals in a direction away from the other and crosswise to the length of the fuse, and non-conducting means lying at the corner between the movable terminal and the fuse for causing the fuse to be drawn about said corner.

3. The combination of an annular terminal having an opening therethrough, a fuse extending across said opening and connected at its ends with said terminal, a second terminal engaging said fuse at a point in said opening, said terminals being relatively non-fusible a spring acting upon one of said terminals and tending to withdraw it from said opening in a direction crosswise of the length of the fuse and non-conducting means lying at the corner between the movable terminal and the fuse for causing the fuse to be drawn about said corner.

4. The combination of a permanent annular terminal, a fuse extending across the opening of said terminal and connected with said annular terminal at points at the side of said opening, a movable terminal engaging said fuse at a point in said opening said terminals being relatively non-fusible and spring means connected with said second mentioned terminal and acting upon the same in a direction crosswise of the length of the fuse.

5. The combination of a permanent annular terminal, a fuse extending across the opening of said terminal and connected with the terminal at the sides of said opening, a second terminal engaging said fuse at a point in said opening said terminals being relatively non-fusible and spring means

connected with said second mentioned terminal and acting upon the same in a direction crosswise of the length of the fuse, said spring means being held normally under tension by said fuse.

6. The combination of a permanent terminal having an opening therethrough, a plurality of fuses extended across said opening at different places and meeting one another at a common point in the opening, a relatively movable terminal engaging said fuses at their common meeting point, said terminals being relatively non-fusible and spring means connected with said second mentioned terminal and acting upon the same in a direction crosswise of the length of said fuses.

7. The combination of a pair of chambers arranged side by side with a wall between the same, a fuse in one of said chambers extending lengthwise of said wall, said fuse having a relatively stationary terminal in said chamber, a spring in the other of said chambers, and a relatively movable terminal connected with said spring and passing through said wall so as to be connected with said fuse and act upon the same in a direction crosswise of its length said stationary terminal lying outside the line of movement of said movable terminal and non-conducting means lying along the line of movement of said movable means and defining a corner about which the arc is drawn.

8. In combination, a tubular casing containing a spring, a second casing secured to the end of said tubular casing, said second casing forming a fuse chamber, a wall between said tubular casing and said second casing, said wall having an aperture therethrough, a stem projecting into said aperture, a transverse supporting wire across said opening, said stem being fastened to the central part of said wire, fuse means controlling the breaking of said wire, said fuse means being contained in said fuse chamber, said stem having a removable top portion adapted to carry the arc and a spring for drawing the stem away from said fuse chamber.

9. The combination of two chambers arranged side by side with a metallic wall between the same, said wall forming a fuse terminal and having an aperture, a fuse in one of said chambers extending across the aperture in said wall and connected to said terminal at the side of said aperture, a spring in the other chamber and a second fuse terminal connected with said spring and extending through the aperture in said wall and connected with said fuse, said spring acting upon said fuse in a direction transversely of its length.

10. The combination of two chambers arranged side by side with a metallic wall between the same, said wall forming a fuse terminal and having an aperture, a fuse in

one of said chambers extending across the aperture in said wall and connected to said terminal at the side of said aperture, a spring in the other chamber and a second 5 fuse terminal connected with said spring and extending through the aperture in said wall and connected with said fuse, said spring acting upon said fuse in a direction transversely of its length, and a closure 10 made of insulating material and arranged to fit said aperture, said closure having a small opening for said second mentioned terminal.

11. The combination of two chambers arranged side by side with a metallic wall between the same, said wall forming a fuse 15 terminal and having an aperture, a fuse in one of said chambers extending across the aperture in said wall and connected to said terminal at the side of said aperture, a spring in the other chamber and a second 20 fuse terminal connected with said spring and extending through the aperture in said wall and connected with said fuse, said 25 spring acting upon said fuse in a direction transversely of its length, and a closure made of insulating material and arranged to fit said aperture, said closure having a small opening for said second mentioned 30 terminal, said spring being held under tension by said fuse.

12. A fuse device comprising a tubular member made of insulating material, a metallic member secured to one end of said 35 tubular member and having a head forming a fuse chamber, arc extinguishing liquid and a spring arranged within said tubular member, a terminal located within said tubular member and engaging the end of said spring 40 nearest said metallic member, an annular portion of said head forming the other terminal, and one or more fuses extended from said terminal formed by said annular portion of said head to said terminal connected with said spring. 45

13. A fuse device comprising an annular terminal, a centrally disposed spring actuated terminal and one or more fuses extended across the opening of said annular terminal to said centrally arranged spring actuated terminal, and an auxiliary fuse extending diametrically of said annular terminal and engaging said centrally disposed spring actuated terminal to hold the same against 50 movement.

14. A fuse device comprising a tubular member of fragile material, a metallic member secured to the end of said tubular member and having a head forming a fuse chamber, arc extinguishing liquid and a spring arranged within said tubular member, a terminal post centrally located within said tubular member at one end thereof and engaging said spring, an annular portion of 55 said head forming the other terminal, main

fuses extended from said head to said post, and an auxiliary fuse of relatively fine strong high resistance wire, also extending between said annular terminal and said post.

15. A fuse device comprising a tubular member of fragile material, a metallic member secured to the end of said tubular member and having a head forming a fuse chamber, arc extinguishing liquid and a spring arranged within said tubular member, a 70 terminal post centrally located within said tubular member at one end thereof and engaging said spring, an annular portion of said head forming the other terminal, main fuses extended from said head to said post, 75 an auxiliary fuse of relatively fine strong high resistance wire, also extending between said annular terminal and said post, and a removable disk forming one side of said fuse chamber. 80

16. A fuse device comprising a tubular member of fragile material, a metallic member secured to the end of said tubular member and having a head forming a fuse chamber, arc extinguishing liquid and a spring 90 arranged within said tubular member, a terminal post centrally located within said tubular member at one end thereof and engaging said spring, an annular portion of said head forming the other terminal, main 95 fuses extended from said head to said post, an auxiliary fuse of relatively fine strong high resistance wire, also extending between said annular terminal and said post, and a removable ring or collar forming part of 100 said head and having a disk removably secured to said ring or collar.

17. In combination, a sleeve of insulation closed at its bottom, a metallic chamber mounted on top of and closing off said 105 sleeve, said chamber comprising a fuse chamber, a wall between said sleeve and said chamber, said wall having an aperture therethrough and having a shoulder about said aperture, a disk of insulating material 110 resting upon said shoulder, said disk having a central hole, a terminal stem projecting through said hole, a wire having its ends fastened to said wall and forming a suspension for said stem, and a spring for pulling 115 said stem through said hole.

18. A fuse device having a fluid tight casing accessible to vapors from the fuse when the fuse blows, said casing having a movable part which normally forms a wall of 120 the casing, but is mounted to permit it to become released and to move outwardly so as to form an opening in the casing to vent the same of the fuse gases, said movable part being held normally in position by solder 125 adapted to release said part when the same is acted upon by the pressure of the fuse operation.

19. The combination of a metallic casing having a fuse chamber, a part of said casing 130

being removable and being held normally in position by solder adapted to yield by the explosion of the fuse so as to vent said casing, a second casing made of insulating material and secured to said first mentioned casing, a spring and arc extinguishing liquid in said second mentioned casing, and a terminal connected with said spring and extended into said first mentioned casing and 10 connected therein to said fuse, there being a wall between said casings through which said terminal passes.

20. The combination of a casing forming a fuse chamber, said casing having a removable part for venting, fuse terminals in said chamber, one of said fuse terminals being movable, means for moving said terminal in a direction away from said vent when the fuse operates, a second casing adjacent to 20 said first casing, said second casing containing means for moving said terminal, and a movable part for venting said second mentioned casing, said part being combined with means for preventing its movement 25 into said second casing, but permitting its movement away from the same and out through the vent in said first mentioned casing.

21. The combination of a tubular member 30 forming a liquid chamber and provided with a movable fuse terminal, and means for shifting said terminal to lengthen the spark gap, a cap member for said tubular member, said cap member having a portion 35 forming a terminal adapted to cooperate with said movable terminal, a top fitted removably to said cap member, said top and cap member forming a fuse chamber, said cap member having an aperture forming an opening between said fuse chamber and the interior of 40 said tubular member, and a disk of insulating material fitted loosely over said aperture, said movable terminal being passed through said disk, and fuse controlled means 45 for holding said movable terminal in position.

22. The combination of a tubular member forming a liquid chamber and provided with a movable fuse terminal, and means 50 for shifting said terminal to lengthen the spark gap, a cap member for said tubular member, said cap member having a portion forming a terminal adapted to cooperate with said movable terminal, a top fitted removably to said cap member, said top and 55 cap member forming a fuse chamber, said cap member having an aperture forming an opening between said fuse chamber and the interior of said tubular member, and a disk 60 of insulating material fitted loosely over said aperture, said movable terminal being passed through said disk, and means for holding said movable terminal in position, said holding means comprising a fine wire 65 adapted to serve as a fuse.

23. The combination of a tubular casing, a second casing located at one end of said first mentioned casing, said second mentioned casing being formed in part by a removable cover, and having a wall portion 70 opposite said cover forming a wall or partition between the two casings, said wall portion having an opening provided with a shoulder nearest said first mentioned casing, a removable closure for said opening, a terminal in said first mentioned casing extending through said closure into the second mentioned casing, a fuse extended across said opening and engaging said terminal, and spring means in the first mentioned casing engaging a portion of said terminal located in said casing. 75

24. The combination of two closed casings located side by side with a wall between them, said wall being provided with an opening between said chambers, a movable closure for said opening, a fuse in one chamber and a spring in the other chamber, said spring having a connection with said fuse extending through said closure said closure 80 being movable out of said opening. 85

25. The combination of a casing forming a fuse chamber, said casing having a removable part for venting, a second casing adjacent to said first casing, said second casing 90 containing a spring and also having a removable part for venting, a fuse in said fuse chamber, and means for connecting said fuse with said spring. 95

26. The combination of a tubular casing 100 made of glass, a metallic casing secured at one end of said tubular casing and forming a closure for such end of the same, a fuse in said metallic casing, and a spring in said tubular casing, connected to said fuse. 105

27. The combination of a tubular casing made of insulating material, a metallic casing secured at one end of said tubular casing and forming a closure for such end of the same, a fuse inclosed within said metallic 110 casing, a spring in said tubular casing, said spring acting to lengthen the distance between the fuse terminals, and a liquid director located within said tubular casing and secured to said spring, said liquid director having a tapering opening, the small end of which is nearest said fuse casing, said fuse casing communicating with said tubular casing through a restricted opening, said liquid director being adapted to project said 115 liquid into said opening. 120

28. The combination of a tubular casing made of insulating material, a metallic casing secured at one end of said tubular casing and forming a closure for such end of the same, a fuse in said metallic casing, a spring held under restraint by said fuse and located in said tubular casing, the partition or wall between said casings being provided with a movable portion, arc extinguishing liquid in 125 130

6

said tubular casing and a liquid director confined within said tubular casing and secured to the spring therein near said fuse casing, said liquid director having a tapering opening the relatively small end of which is adjacent said fuse casing and in proximity to said movable portion, said liquid director being adapted to project liquid through the opening in the wall between the tubular casing and the metallic casing which opening is normally closed by said movable portion.

29. The combination of a tubular casing containing a spring, a second casing secured to one end of said tubular casing and forming a fuse chamber, a fuse in said chamber, and a terminal connecting said spring and fuse, said terminal comprising an upper removable end part which is adapted to carry the arc.

30. In a fuse of the class described, a sleeve forming the main body of the fuse, a body of arc extinguishing liquid in said sleeve, a stationary terminal external to said sleeve, a movable terminal having a part thereof external to said sleeve, a fusible element connected between said stationary terminal and the part of said movable terminal which is external to said sleeve, means for moving said movable terminal entirely into said sleeve and for bringing the same into contact with said body of liquid, and a separate inclosing casing inclosing said stationary terminal and said fuse, and a portion of said movable terminal, said casing being mechanically connected to said sleeve, and external to said sleeve.

31. In a fuse of the class described, a chamber substantially filled with arc extinguishing liquid, a second chamber adjacent to said first chamber, but external thereto, a fusible member in said second chamber, said second chamber having means to vent an explosion of the fuse externally of said first chamber, a relatively movable terminal connected to said fuse and projecting into the second chamber from the first chamber, and

means for moving said terminal out of said second chamber and into said arc extinguishing liquid.

32. In a fuse, a main body comprising a sleeve of insulation, substantially full of arc extinguishing liquid, a relatively movable terminal extending above said sleeve and out of said liquid, a fuse connected to said terminal, a fuse chamber above said sleeve for inclosing the fuse and a relatively stationary terminal for said fuse in said chamber, said fuse chamber being organized to keep the gases from a fuse explosion out of the sleeve.

33. In a fuse, a main body comprising a hollow cylinder of insulation, said cylinder being substantially filled with arc extinguishing liquid, a fuse chamber above and external to said sleeve and united to said sleeve, a fuse in said chamber, a terminal projecting into said chamber from said sleeve, means to vent said chamber independently of said sleeve, and means for moving said terminal out of said chamber into the liquid in said sleeve.

34. In a fuse, a main body comprising a sleeve of insulation, said sleeve being substantially filled with arc extinguishing liquid, a fusible member, a relatively movable stud or terminal connected to said fusible member, a cylindrical fuse chamber for inclosing said fuse secured to said sleeve, said chamber being short in length relative to its diameter, and having a lower and an upper wall, the lower wall being perforated to receive the end of said stud or terminal, the opening in said wall being above and out of said liquid, and independent means to move said stud or terminal out of said chamber into said liquid.

In witness whereof, I hereunto subscribe my name this 31st day of March, A. D. 1914.

NICHOLAS J. CONRAD.
